CLOSURE

Louis Schumacher, Brooklyn, N. Y.

Application August 10, 1933, Serial No. 684,473

15 Claims. (Cl. 221—60)

This invention relates to devices such as closures for collapsible tubes or the like.

Among the objects of this invention is to provide a device of the character described having improved means for effecting an inexpensive airtight closure and one which can be readily opened; a closure which has an improved stop engagement; a closure having few and simple parts and which is neat in appearance, and is adapted for quantity production, and which shall have a neat and uniform port, and which closure is convenient, reliable, and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary enlarged view in vertical cross section showing a device embodying the invention, in initial or factory assembled closed position.

Fig. 2 is a similar view thereof, in open position, with the interlocking engagement modified.

Fig. 3 is an enlarged sectional view taken on line 3—3 of Fig. 1.

Figs. 4 and 5 are fragmentary enlarged sectional views of modifications of the invention.

Figs. 6 and 7 are fragmentary vertical sectional views of modifications of the invention in respectively open and closed positions.

Fig. 8 is a fragmentary vertical sectional view of a further modification of the invention.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Heretofore it has been known to provide a closure such as that shown in U. S. Patent No. 1,910,378, issued May 23rd, 1933, wherein the soft metal neck of the collapsible tube was expanded for a tight seat and had a closed bulge portion

for resiliently engaging in the port of the cap. This, however, did not satisfy the quest in the art for a hermetic seal, and a closure was developed wherein the said neck was provided with a closed ended projection to be sheared off by the cap, as disclosed in pending applications. While this latter closure is initially fully airtight, difficulties were encountered in shearing the projection, since the metal would tend to tear with consequent deformation of the seating portion of the neck. Moreover, the port formed in the neck by the shearing would have an objectionable ragged edge, or shavings would result from the shearing and enter the contents discharged from the tube. To form a sharp edge for the shearing action was either too expensive or impractical since the cap is made of a composition material such as "Bakelite". Moreover, the manufacture was difficult since the wall of the projection had to be thinned down very fine to be capable of being easily sheared, and such thinning would sometimes break the metal. This invention was devised to overcome these difficulties.

In considering the foregoing difficulties, it is important to bear in mind that the cap port must be eccentric, since various devices adapted for concentric action can not be used in this closure.

Referring in detail to the drawing, 10 denotes a device embodying the invention. The same may include, for example, a collapsible container 11 having a neck 12 having a wall or dome 13, or the equivalent, and a port such as 14. Movable along the wall or dome is a closure member such as a cap 15 which may be journaled on the neck for controlling the port 14, and having a port 16. The member 15 may be secured to the neck in a suitable manner as by mating annular grooves and ridges 17, 18 in the cap and neck respectively. These elements 17, 18 may snugly fit each other as shown at 17a and 18a in Fig. 2, but preferably a small clearance may be observed therebetween and between the upper and lower margins or corners of the elements, although said corners may snugly fit each other. Moreover, the elements 17, 18 may be vertically elongated as compared with the corresponding elements of Fig. 2 to provide a degree of resilience in the fastening, whereby the cap and dome may be sprung apart as shown in Fig. 6. This resilient fastening is intended to be illustrative.

Between the dome and the cap is a seating surface 13a, and one of the cap and neck elements is provided with a sealing projection extending past the seating surface into engagement

with the other element. More particularly, one of the elements, such as the cap, is formed at its seating surface with an irregularity, such as a sealing recess 19, and the marginal region or edge 20 is bent into the recess to snugly engage the peripheral edge of the latter. Preferably the bent edge forms an annular sealing lip pressed into the recess in situ to accurately conform to the recess. Since the sealing lip or neck 10 is made of a yielding material, such as a soft metal, a tight closure for the port 14 is obtained. The cap 15 may be made of a rigid material such as "Bakelite". Desirably, the diameter of the annular lip may be greater than that of the cap port 16.

The device 10 may be made by a spinning operation to form the ridge 18 and simultaneously the lip 20. Also fluid pressure or the pressure of a yielding or elastic material such as rubber, of a suitable hardness or toughness may be used, to simultaneously form the ridge and sealing lip, according to the principles of U. S. Patent Nos. 601,825 of April 5th, 1898, and 616,764 of December 27th, 1898. In that case the rubber tool head may be so formed and applied as not to exert maximum pressure in forming the ridge 18, although maximum pressure may be used to form the sealing lip 20. However, the sealing lip 20 may be preformed, and then expanded tightly 30 into the recess.

In use, the cap 15 is rotated to a position such as shown in Fig. 2, and the sealing lip 20 is flattened or ironed out by the edges of the recess 19, and by the hard seating surface of the cap. Preferably, no shear of any part of the sealing lip occurs. This can be controlled by the hardness of the sealing lip, its height, the character and curvature of the recess walls, the hardness and nature of the cap material, and other like factors. However, if desired, a curved projection 21 may be provided in the recess of less height than the depth of the recess to facilitate the substantial flattening down of all parts of the sealing lip as shown in Fig. 2 forming the port 14a. The resilient action of the dome 13 and of the fastening means 17, 18, or both, may aid by permitting a slight separation of the cap and dome as shown in Fig. 6, so that the sealing lip may become flattened by repeated rotations of the cap, in normal use. However, the structure shown in Fig. 6 may also be considered as including a relatively hard sealing lip 20a, and one which is not intended normally to be flattened or ironed out, or only to a slight degree. The diameter of this hard sealing lip is intended to be greater than that of the port 16, and it may snap into the recess 19 when the device is closed. The diameter of this sealing lip may also be such as to permit it to snap into port 16.

It will be appreciated that the sealing lip affords a desirable stop engagement with the recess to snugly maintain the device initially closed, but after the same is once opened such stop engagement may become slight or wholly disappear. In Figs. 4 and 5 are shown different relations of the sealing lip and the recess. In the latter, the recess 19a is sufficiently shallow, or the sealing lip sufficiently high to cause not only the exterior sides 22 of the sealing lip to engage the recess, but also the edge 23 thereof to snugly engage the opposite plane or curved wall of the recess. In Fig. 4, the recess 19b is of relatively greater depth so that only the sides of the sealing lip engage the recess.

It will be understood that the sealing lip may

vary in height between three and ten to twenty thousandths of an inch, or thereabouts, these figures being illustrative.

In Fig. 6, the recess 19c may have a curved wall 19d as distinguished from the corresponding plane or oppositely curved walls of Figs. 5 and 4, respectively. However, the latter walls may be more desirable for concentrating the pressure of a rubber head laterally in the recess and against the sealing lips.

In Fig. 7 is shown a device 24 embodying the invention. The same includes a neck 25, or the like, having a port 26, and a movable closure or cap 27 which may have a port 28. The cap may have an irregularity or sealing projection 29 extending beyond the seating surface 30 between the cap and the wall or dome 31, and being of any suitable conformation. Said sealing projection may have a greater diameter than the port 26, and the latter may have a marginal sealing lip 32 inwardly deformed into tight engagement around the projection. The difference in diameters may vary, for illustration, between six and thirty thousandths of an inch. This device may be manufactured in the same manner as the device 10, by internal expansive pressure in the neck, and may be otherwise precisely similar in construction with the devices shown in Figs. 1 to 6. In the device 24, the lip 32 is not materially affected in turning the cap, and the dome or fastening means 17, 18 or both may be relied upon for resilience to permit the projection to be sprung out of the port 26 upon rotation of the cap, according to the principle illustrated in Fig. 6.

In Fig. 8 is shown a modification of the invention including a closure or cap 35 having a port 36 and a seating surface consisting of any soft yielding material, such as a paraffin or adhesive composition or celluloid or other suitable material forming a continuous uniform layer 37. The neck 38 may have a port 39 and an annular uniform projecting lip 40 projecting into or embedded in said layer to form a particularly tight seal. On rotating the cap, the lip may slip over the layer, or may scoop a groove therein. In making this device, the lip may be preformed, or it may be formed by internal expansive pressure as hereinbefore described, and the sealing lip will be embedded by reason of greater expansive pressure at the edge of the port 39. Such layer may also be used in the devices 10 and 24 if desired. The layer 37 may be formed by merely dipping the cap in a self hardening liquid, or by spraying the liquid into the cap. The device is otherwise the same as that shown in the other figures; but no preformed recess is made, as the sealing lip forms its own recess.

By the terms tube or tubular element or tube neck as used herein is meant any tubular member, or container, receptacle, tank or can. By the terms cap, or cap element is meant any type of closure or control member or means that is usable for the purposes of the invention. The term rotary is employed as signifying an angular motion.

It will be appreciated that various changes and modifications may be made in the device as shown in the drawing, and that the same is submitted in an illustrative and not in a limiting sense, the scope of the invention being defined in the following claims. The sizes of the sealing lips and associated parts may in each case vary with the size of the closure as a whole.

I claim:

1. In a collapsible container, a tubular element having an opening, a closure element for controlling said opening, said closure element having an outlet adapted to be brought into register with said opening said elements having a common seating surface therebetween, said closure element having an irregularity at said seating surface, said opening having its edge continuously deformed to conform to said irregularity for tightly closing said opening, and said elements being slightly separable at said seating surface for disengagement of said deformed edge and said irregularity.
2. In a collapsible container, a tube portion having an opening offset from the axis of the tube portion, a cap on said tube portion for controlling said opening, said tube portion having the rim of said opening constituting a yieldable lip, and said cap having an internal recess offset from the axis thereof for receiving said lip, said recess conforming substantially to the shape of the lip to snugly receive the same to form with said lip a tight closure for said opening, and said lip being laterally deformable, as set forth.
3. In a collapsible container, a tubular element, a closure cap therefor, and resilient means rotatably interconnecting said cap and element so as to allow for resilient movement of the cap axially of said element, said resilient means including a bead portion integral with the tubular element.
4. In a collapsible container, a tubular element having an opening offset from the axis thereof, said opening having a lip forming rim, and a rotary closure for said opening having means for sealingly engaging said lip and for flattening the same on rotation of said closure, to break the seal.
5. In a collapsible container, a tubular element having an opening provided with an externally projecting lipped rim, said opening being offset from the axis of the tubular element, and a member movably mounted on said element for controlling said opening and having means offset from the axis of the member for continuously engaging said lipped rim along a side thereof and for flattening the same upon movement of the member.
6. In a collapsible container, a tube portion having an opening offset from the axis thereof, a cap movably seated on the tube portion for controlling said opening, said cap having an irregularity offset from the cap axis, said opening having a substantially continuous marginal yieldable lip projecting toward the cap, said lip and irregularity being arranged so that one receives the other in snug substantially continuous engagement, and the lip being adapted to be substantially flattened out on relative movement between the cap and tube portion.
7. In a collapsible container, a tubular element having an opening offset from the axis thereof, a closure element seated on the tubular element for controlling said opening, the tubular element having an upstanding marginal yieldable lip along the edge of said opening, the closure element having a recess offset from the axis thereof for snugly receiving the lip, and the closure element having a slight projection substantially central of the recess and projecting into the opening defined by the lip, as set forth.
8. In a collapsible container, a tubular element having an opening offset from the axis thereof and having a yielding marginal lip, a rotary closure element for controlling said opening, said closure element having a recess offset from the axis thereof for snugly receiving the lip, and the closure element having a slight projection substantially central of the recess and projecting into the opening defined by the lip, as set forth.
- closure element having a recess offset from the axis thereof for snugly receiving said lip and a slight cam shaped flattening projection within said recess and lip releasable therefrom on rotation of said closure element.
9. In a collapsible container, a tubular element having a marginally lipped opening offset from the axis thereof, a non-removable cap on said element for said opening, said cap having a yielding internal surface portion offset from the axis of the cap and into which the marginal lip extends, as set forth.
10. In a collapsible container, a tube portion having an opening offset from the axis thereof, a non-removable cap on said tube portion movable between open and closed positions for controlling said opening, said cap having an outlet offset from the axis thereof and adapted to be brought into register with the opening thereof upon movement of the cap into open position, said tube portion having a lip extending peripherally along its opening and projecting into a recess in the surface of the cap in the closed position thereof.
11. In a collapsible container, a tube portion having an opening offset from the axis of the tube portion, a cap on said tube portion movable between open and closed positions for controlling said opening, said cap having an outlet offset from the axis of said cap adapted to be brought into register with the tube opening on movement of the cap into open position, said tube portion having a peripheral lip about said opening, and said cap having an internal recess for snugly receiving said lip in the closed position of the cap.
12. In a collapsible container, a tubular element having an opening offset from the axis of the tubular element, a cap element journaled on said tubular element for controlling said opening, said cap element having an outlet offset from the axis of the cap element and adapted to be brought into and out of register with the opening of the tubular element by rotation of the cap element, said cap element having a recess, and means projecting from said tubular element toward the other element and extending into said recess to afford a closure engagement between said elements along the edge of said opening, said means including a peripheral sealing lip for said opening, said means affording a yieldable engagement between the elements, releasable by a rotational movement of the cap element.
13. In a collapsible container, a tubular element having an axially offset opening, a rotary cap element on said tubular element for controlling said opening, said cap element having an outlet and an internal recess both offset from the axis of the cap and being in angularly spaced relation to each other, said elements having a common seating surface therebetween in communication with said opening, and the tubular element having a yielding peripheral lip for said opening projecting past said seating surface into said recess when in one position to afford a snug closure engagement between said elements along the edge of said opening.
14. In a collapsible container, a tubular element having an axially offset opening, a cap element for controlling said opening and having an outlet offset from the axis thereof, said elements having seating surfaces therebetween and means extending between the seating surfaces, said means including an irregularity member on the

cap element at said seating surface, and a yielding lip member along the rim of said opening continuously projecting toward and conforming to said irregularity member for tightly closing said opening, one of said members being received in the other member and the members being adapted to be released from each other on turning the cap element.

15. In a collapsible tube, a tube neck having

a port and an integral outwardly deformed thin walled pliable lip extending continuously along the margin of the port, said lip being substantially smaller in diameter than the tube neck, and a cap movably seated on the tube neck for controlling the port, said cap having a recess in the internal face thereof for snugly receiving the wall of the lip, as set forth.

LOUIS SCHUMACHER.
